US00D564967S

(12) **United States Design Patent** (10) **Patent No.:** **US D564,967 S**
Kudo (45) **Date of Patent:** **** Mar. 25, 2008**

(54) **ELECTRICAL CONNECTOR**

(75) Inventor: **Tsutomu Kudo**, Ibaragi (JP)

(73) Assignee: **Tyco Electronics AMP KK**,
Kanagawa-Ken (JP)

(**) Term: **14 Years**

(21) Appl. No.: **29/244,837**

(22) Filed: **Dec. 14, 2005**

(30) **Foreign Application Priority Data**

Jun. 17, 2005 (JP) 2005-017686
Jun. 17, 2005 (JP) 2005-017687

(51) **LOC (8) Cl.** **13-03**

(52) **U.S. Cl.** **D13/147**

(57) **CLAIM**

The ornamental design for an electrical connector, as shown and described.

DESCRIPTION

FIG. 1 is a front elevation view of an electrical connector, showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a top, front and right side perspective view thereof; and,

FIG. 8 is a bottom, rear and left side perspective view thereof.

1 Claim, 8 Drawing Sheets
